UNITED STATES PATENT OFFICE.

JOHN KANE AND FORREST J. COUCH, OF ROCHESTER, NEW YORK, ASSIGNEES TO
AMERICAN LAUNDRY MACHINERY CO., OF CINCINNATI, OHIO, A CORPORATION
OF OHIO.

TREADLE MECHANISM.

1,252,582.

Specification of Letters Patent.

Patented Jan. 8, 1918.

Application filed November 20, 1915. Serial No. 62,678.

To all whom it may concern:

Be it known that we, JOHN KANE and FORREST J. COUCH, both of Rochester, in the county of Monroe and State of New York, 5 have invented certain new and useful Improvements in Treadle Mechanism; and we do hereby declare the following to be a full, clear, and exact description of the same, reference being had to the accompanying drawings, forming a part of this specification, and 10 to the reference-numerals marked thereon.

Our invention relates to treadle mechanisms of the type generally employed in conjunction with various types of apparatus 15 designed for foot control, such as ironing machines, presses and the like, and it has for its particular purpose to afford a simplified construction, that permits a single treadle to be employed in a double capacity, 20 to effect operation of the machine and to restore the parts after the operation to their normal position. A further object of the invention is to lessen the cost of construction by eliminating one treadle from the usual 25 double treadle arrangement, in which one treadle is employed for operating and a second treadle for releasing or restoring the parts. A further advantage of the improvement is found in the reduction of labor 30 which it causes, since the operator does not need to change the position of the foot which is used to control the treadle, as the latter is operated from different positions and in varying relations, in order to effect the desired 35 movements of the other parts of the mechanism. To these and other ends the invention resides in certain improvements and combinations of parts all as will be hereinafter more fully described, the novel features being pointed out in the claims at the 40 end of the specification.

In the drawings:

Figure 1 is a side elevation of an ironing machine with the invention applied, and 45 showing the position of the parts when the machine is in its operating position;

Fig. 2 is an elevation of the treadle mechanism, showing the position of the operating lever and other parts after the initial 50 releasing movement of the controlling member or treadle;

Fig. 3 is a similar view after the parts are completely restored to normal position;

Fig. 4 is a sectional view in a horizontal

plane showing the treadle mechanism in 55 plan.

Similar reference characters throughout the several figures indicate the same parts.

The scope of the invention is not to be limited in any sense to the particular application or form of mechanism that is set forth in the present case, as it may be otherwise applied in connection with any mechanism involving an operating lever arranged for movement in opposite directions and 60 connected with a controlling member for effecting its opposite movements. In the arrangement shown, which is illustrative of a preferred construction, we employ a base 1 and a vertical frame 2 on which is mounted 70 a stationary ironing and pressing member or chest 3 adapted to be heated by a suitable fluid medium that is supplied through the pipes 4. Arranged for co-operation with the heated member 3 is a vertically movable bed 75 that is carried upon a movable frame which is connected for operation to a toggle joint consisting of links 5 and 6, the latter forming part of an operating lever 7 which is pivotally mounted on a post 8 supported in 80 the base 1.

The operating lever 7 has pivoted at its outer end a controlling member or treadle 10 which is provided with a downwardly projecting lug 11 at a point near its connection with the lever 7, and arranged to engage the base flange 12 and constitute a fulcrum in the manner shown in Fig. 1. The operating lever 7 carries an overhanging portion 13 which engages an extension 14 85 formed on the controlling member in the manner shown in Fig. 3 to form a stop, while 15 is an upstanding portion or toe guard at the front end of the treadle 10. The link 6 preferably carries a spring 16 which acts 90 as a buffer and engages the abutment 17 to prevent excessive shock, as the parts are returned to their normal position, shown in 95 Fig. 3.

The operation of the device may be described briefly as follows: With the parts in the position illustrated in Fig. 3, in order to effect operation of the machine the outer end of the controlling member 10 is engaged and depressed, and by reason of the 100 engagement of the extension 14 with the portion 13, the operating lever is caused to move downwardly, and the controlling member

moves bodily with it. The lever swings about its axis and straightens the toggle joint to bring the ironing members into ironing relation. The parts are then in the position shown in Fig. 1. To release the mechanism and restore the parts to normal position, the inner end of the controlling member 10 is depressed, rocking the treadle on the projection 11 as a fulcrum and thereby causing the outer end of the operating lever to move slightly in an upward direction in the manner shown in Fig. 2, until the toggle joint is broken. The weight of the parts is then sufficient to complete the restoring operation, moving the operating lever upwardly until it assumes the position shown in Fig. 3, after which the parts are ready for a second operation. It will be seen that the controlling member is thus moved about separate or independent fulcrums, afforded by pivotal axis 8 and projection 11, to effect opposite movements of the lever, and movement of the treadle about axis 8 is, in the present instance, caused by the overhanging portion 13 arranged on the opposite side of lever 7 from projection 11, and engaging extension 14 to cause the controlling member to move bodily with the lever.

Copies of this patent may be obtained for five cents each, by addressing the "Commissioner of Patents, Washington, D. C."

We claim as our invention:

1. The combination with an operating lever, of a controlling member pivoted to the operating lever, a stop on the lever which limits the relative movement of the controlling member in one direction, and a projection on the controlling member which serves as a fulcrum when it is moved in the opposite direction relatively to the lever. 30
2. The combination with an operating lever, of a controlling member pivoted thereto, and independent fulcrums about which the controlling member is operable in order to effect movement of the lever in opposite directions. 40
3. The combination with an operating lever, of a controlling member pivoted thereto and movable bodily in one direction with said lever and in the opposite direction about a fulcrum near its connection with the lever, to effect corresponding movements of the lever. 45

JOHN KANE.
FORREST J. COUCH.
